UNITED STATES PATENT OFFICE.

ARTHUR POWELL AND C B NEAL, OF McALESTER, OKLAHOMA.

RAIL JOINT.

Application filed April 13, 1922. Serial No. 552,123.

To all whom it may concern:

Be it known that we, ARTHUR POWELL and C B NEAL, citizens of the United States, residing at McAlester, in the county 5 of Pittsburg and State of Oklahoma, have invented certain new and useful Improvements in Rail Joints; and we do hereby declare the following to be a full, clear, and exact description of the invention, such as 10 will enable others skilled in the art to which it appertains to make and use the same.

This invention relates to new and useful improvements in rail joints or couplings and has for its primary object the provision of 15 means whereby the ends of rails may be easily and quickly and positively locked together and within a chair without the use of bolts or similar fastenings, and also whereby the rails may be set for any de- 20 sired expansion or contraction.

Another object of this invention is the provision of inclined seats in the chair to receive rollers adapted to wedge against the rails to firmly secure them to the chair 25 and any tendency of the rails to separate causing an increased securing action of the rollers to the rails, owing to the inclination of the seats, consequently obviating any chance of separation of the rails or their 30 disconnection from the chair.

A further object of this invention is the provision of a rail joint of the above stated character which will be simple, durable and efficient, and which may be manufactured 35 and sold at a comparatively low cost.

With these and other objects in view, as will become more apparent as the description proceeds, the invention consists in certain novel features of construction, combination and arrangement of parts as will be hereinafter more fully described and claimed.

For a complete understanding of our invention, reference is to be had to the following description and accompanying drawing, in which:

Figure 1 is a side elevation, illustrating a rail joint constructed in accordance with our invention,

Figure 2 is a longitudinal sectional view, illustrating the same,

Figure 3 is a transverse sectional view, illustrating the device.

Referring in detail to the drawing, the 55 numeral 1 indicates a chair adapted to receive the opposing ends of rails 2 and 3

and comprises a base 4 on which the rails rest and is provided with spike receiving notches 5 in its edges to receive the ordinary securing spikes. Formed on the base 4 are the side plates 6 that extend upwardly and inwardly to engage the webs and treads of the rails to prevent the latter from shifting laterally upon the base. The base is provided with a cut out portion 7 between 60 its ends to provide a roller chamber 9. The bottom wall of the chamber inclines upwardly towards its ends 8 for the purpose of forming upwardly inclined seats 10 that incline upwardly towards the ends of the 65 base, or in other words, incline in opposite directions to each other. The lower ends of said seats terminate in sockets or recesses 11 adapted to receive rollers 12. The rollers, while resting in the recesses or sockets, permit the rails to be placed in and removed 70 from the chairs, it being understood that the rails are inserted into the chairs by way of the ends of the latter. The side plates are provided with inclined slots 13 to give 75 access to the rollers for the purpose of holding the rollers against travel along inclined seats 10 when it is desired to remove or free the rails. As the rails are moved away from each other in the chair the rollers by 80 traction travel upon the inclined seats and wedge tightly against the bases of the rails to firmly secure them within the chair against accidental separation from the chair or relatively to each other. When it is de- 85 sired to remove the rails, the rollers are held in the recesses or sockets 11 by a suitable instrument or tool inserted into the slots 13 so that they will not travel along seats 12. The side plates intermediate their ends are 90 provided with alining slots 14 which permit the rollers to be placed in and removed from the roller chamber when desired in the absence of the rails.

If desired balls may be used in lieu of 100 the rollers by changing the shape of the seats to fit balls, and any number of rollers or balls may be used by increasing the length of the chair and the number of seats. The chair may be of a single casting or 105 contain separate parts if desired.

From the foregoing description taken in connection with the accompanying drawing, it should be apparent that a very effective securing means has been provided for the 110 opposing ends of rails and which obviates the necessity of providing or using bolts

or similar fastenings to pass through the webs of the rails and also through tie plates or chairs, and the device is capable of use in any character of railroad track.

5 While we have shown and described the preferred embodiment of our invention, it will be understood that minor changes in construction, combination and arrangement of parts may be made without departing 10 from the spirit and scope of the invention as claimed.

Having thus described our invention, what we claim is:

1. A rail joint comprising a chair adapted 15 to slidably receive rails in an endwise direction, inclined seats at intersecting angles on said chair, and wedging means movable along said seats and constituting a support for the rails so that during their movement 20 away from each other said wedging means will wedge against said rails and chair to firmly lock the rails against separation.

2. A rail joint comprising a chair having a roller chamber and adapted to receive the 25 opposing ends of rails, oppositely inclined seats formed in said chamber, said chair having slots and recesses communicating

with said seats, and rollers located in said recesses and engaging said seats and constituting supports for the rails and adapted to 30 wedge against the inclined seats and the bottom of the rails through longitudinal displacing movement of the latter, said slots permitting an instrument to enter the chamber for the purpose of positioning the rollers against movement on said seat during movement of the rails and to free the rails from the chair.

3. A rail joint comprising a base, side plates formed on said base having oppositely 40 inclined slots, inclined seats formed on the base between said plates and adjacent the slots, rollers engaging said seats and the rails, said plates intermediate their ends having slots to permit the rollers to be 45 placed in and removed from the seats when the rails are out of place.

In testimony whereof we affix our signatures in presence of two witnesses.

ARTHUR POWELL,
C B NEAL.
